UNITED STATES PATENT OFFICE.

ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

CUT-OUT-SWITCH APPARATUS.

Application filed October 6, 1919. Serial No. 328,841.

To all whom it may concern:

Be it known that I, ANDREW H. CANDEE, a citizen of the United States, and a resident of Pittsburgh, in the county of Allegheny and State of Pennsylvania, have invented a new and useful Improvement in Cut-Out-Switch Apparatus, of which the following is a specification.

My invention relates to cut-out switch apparatus for dynamo-electric machines, and it has special relation to switch means for cutting out either motor of a two-motor railway equipment.

In the prior art, the cut-out switch apparatus for a two-motor equipment has comprised two independent double-pole, double-throw switches for individually excluding the respective motors from circuit and, consequently, this switch apparatus has occupied a space comparable to that which would be necessary for a four-pole double-throw switch. On the other hand, the customary cut-out switch for four-motor equipments has been a triple-pole, double-throw switch. Consequently, the operating space for a four-motor cut-out switch has been only three-fourths of the operating space required for the prior art two-motor cut-out apparatus.

For interchangeability, as well as for saving space and for more nearly standardizing cut-out apparatus for the two types of equipments, it is desirable to have the two-motor cut-out switches fit in the same space as that required for the four-motor cut-out switches, namely, substantially the same operating space as an equal-capacity, triple-pole, double-throw switch. One object of my invention, therefore, is to provide such a two-motor cut-out switch.

Another object of my invention is to provide switch means for cutting out either motor of a two-motor equipment comprising two movable switch elements, each equivalent to a single-pole, single-throw switch and a double-pole, single-throw switch.

A further object of my invention is to provide cut-out switch means of the character in question comprising two movable switch elements having one member in common.

Still another object of my invention is to provide double-throw switch means for cutting out either motor and having two

members in substantial alignment for preventing the actuation of both switch means to the cutting-out position.

Other objects of my invention, directed toward compactness, simplicity and reliability, will become evident from the following detailed description, taken in conjunction with the accompanying drawing, wherein—

Figure 1 is a diagrammatic view of a system of control embodying my present invention;

Fig. 2 and Fig. 3 are views, respectively in front elevation and in end elevation, of the preferred form of my cut-out switch apparatus;

Fig. 4 is a detail view of one part of the cut-out switch; and

Fig. 5 and Fig. 6 are detail views of portions of the cut-out switch constructed in accordance with another form of my invention.

Referring to Fig. 1, the system here shown comprises suitable supply-circuit conductors Trolley and Ground; a plurality of vehicle-propelling motors M1 and M2; an accelerating resistor 1; a cut-out switch apparatus 2; and a plurality of controlling switches for the motors including a line switch LS, resistor-short-circuiting switches R1 to R4, inclusive, a series-connecting switch S and a pair of parallel-connecting switches P and G.

The motors M1 and M2 are shown as being of a familiar direct-current type, respectively having commutator-type armatures A1 and A2 and series field windings F1 and F2.

The cut-out switch apparatus 2 comprises two movable switch elements, respectively designated as 2_{M1} and 2_{M2}, for respectively cutting the motors M1 and M2 out of circuit.

The stationary contact members or switch jaws for the cut-out switch 2 are nine in number, being arranged in three vertical rows of three each and respectively numbered from 3 to 11, inclusive. The intermediate horizontal row comprising jaws 4, 7 and 10 is of the familiar hinge or pivot variety, while the remaining jaws are of the well-known bifurcated type for receiving flat switch blades.

The movable switch element for the cut-out switch portion 2_{M1} comprises a plurality

of parallel-extending blades 12 and 13, the upper ends of which are joined by an insulating handle 14, and the lower ends of which are respectively hinged to switch 5 jaws 4 and 7. A similar switch portion for cutting out the other motor M2 comprises two parallel-extending blades 15 and 16, the outer ends of which are joined by an insulating handle 17, while the inner ends thereof are respectively hinged to jaws 7 and 10. A single offset switch blade 18 is rigidly secured to the blade 12 and a similar offset blade 19 is securely fastened to the blade 16.

Consequently, the cut-out switch apparatus 15 2 comprises nine stationary contact terminals or switch jaws arranged in a rectangle and two similar movable switch elements each being equivalent to a double-pole, single-throw switch and a single-pole, single-throw switch of the knife-blade type. Furthermore, the operating space required for the complete cut-out switch is equivalent to that necessary for an equal-capacity, triple-pole, double-throw switch.

25 Assuming that the cut-out switch elements normally occupy the illustrated opposite positions, wherein the double-throw portions are actively connected, the motors may be started into operation by the closure of the line switch LS, switch R1 and the series-connecting switch S. Since an auxiliary control system for actuating the various illustrated switches in the desired order may be readily devised by those skilled in the art, 30 I have not deemed it necessary to illustrate or describe any such system, particularly since the connections of the system, outside of the cut-out switch arrangement, are well known.

40 With the switches LS, R1 and S closed, a circuit is established from the Trolley through conductor 25, switches LS and R1, conductor 26, the entire accelerating resistor 1, conductor 27, switch jaw 7, blade 13, 45 jaw 6, conductor 28, armature A1, field winding F1, junction-point 29, conductor 30, switch jaw 3, blade 12, jaw 4, conductor 31, switch jaw 10, blade 16, jaw 11, conductor 32, series-connecting switch S, conductor 33, 50 armature A2, field winding F2 and conductor 34 to Ground. The motors are thus connected in series relation with the accelerating resistor across the supply circuit, in accordance with the usual practice.

55 The various short-circuiting switches R1 to R4, inclusive, are then manipulated in any preferred order to gradually short-circuit the resistor 1 and accelerate the motors to full-series relation. By closure of the 60 switch P, opening of the switch S and consequent closure of the switch G, the familiar "shunting" type of transition to parallel relation of the motors is effected.

Under such conditions, the motor circuits 65 may be traced as follows: from the resistor

1, through conductor 27, switch jaw 7, blade 13, jaw 6, conductor 28, motor M1 to junction-point 29, where a new circuit is continued through conductor 36, switch G and conductors 37 and 34 to Ground. A branch 70 circuit is continued from the switch jaw 7 through blade 15, jaw 8, conductors 38 and 39, switch P, conductor 33, motor M2 and conductor 34 to Ground. The accelerating resistor 1 may then be again gradually excluded from circuit to accelerate the motors to full-parallel condition.

75 However, in case the motor M1 is grounded or otherwise damaged so that it is necessary to operate the vehicle by means of the motor M2 alone, the cut-out switch portion 2_{M1} is thrown to its opposite position by means of the handle 14, whereby the blades 12 and 13 are disengaged from the jaws 3 and 6, while the offset blade 18 engages the 80 jaw 5.

85 Under such conditions, the motor M1 is cut out of circuit, as will be evident from the following tracing of the circuits: from the resistor 1, a circuit is continued 90 through conductor 27, switch jaw 7, blade 15, jaw 8, conductor 38, jaw 5, offset blade 18, jaw 4, conductor 31, jaw 10, blade 16, jaw 11, conductor 32, and thence through switch S and the motor M2 to Ground, as 95 previously explained.

90 If the master controller (not shown) is thrown to its parallel position, the switches P and G will be closed and the switch S opened, as previously explained, but no 100 change in the circuit of the motor M1 will occur, although the switch G will ground one terminal thereof. However, since the respective terminals of the motor M1 are connected to switch jaws 6 and 3, which 105 are entirely disconnected from the system when the cut-out switch portion 2_{M1} is thrown to its cut-out position, it follows that no energization of the motor M1 can 110 occur.

115 In the event that the motor M2 be damaged and it becomes necessary to remove it from circuit, the other cut-out switch portion 2_{M2} is thrown to its upper or cut-out position, whereupon a circuit is continued from the resistor 1 through conductor 27, switch blade 13, conductor 28, motor M1, conductor 30, switch blade 12, conductor 31, switch jaw 10, offset blade 19, jaw 9, and conductor 41 to Ground.

120 Since the left-hand terminal of the switch P is connected through conductors 39 and 38 to the switch jaw 8, while the right-hand terminal of switch S is connected through conductor 32 to switch jaw 11, it follows 125 that both of these switches are cut out of circuit when the cut-out switch portion 2_{M2} is thrown to its upper position. One terminal of the motor M2 remains grounded through conductor 34, but no energization 130

of the motor can occur by reason of the arrangement just mentioned.

If the master controller (not shown) should be thrown to its parallel position, 5 the switch G will be closed to connect one terminal of the motor M1 to Ground through conductor 36, switch G and conductors 37 and 34; but, since the same terminal is already grounded through a circuit 10 including conductors 30, 31 and 41, it follows that no circuit changes will be effected by such closure of the switch G.

Consequently, the illustrated cut-out switch arrangement provides for complete 15 removal from circuit of either of the two motors M1 and M2, whether the master controller (not shown) occupies either its series- or its parallel-connecting positions.

The preferred form of my cut-out switch 20 apparatus is shown in Fig. 2 and Fig. 3, wherein the structure illustrated comprises a suitable base or panel 42 upon which are mounted a plurality of stationary switch jaws 43 to 51, inclusive, respectively corresponding 25 to the diagrammatically illustrated switch jaws 3 to 11, inclusive, in Fig. 1. The middle horizontal row of jaws 44, 47 and 50 are of the familiar hinge or pivot type, the associated switch blades being 30 loosely bolted in position. The remaining switch jaws are of the familiar bifurcated or double-blade type for resiliently receiving the single blades of the movable switch elements, as will be clear from their similarity 35 to ordinary knife-blade switches.

A plurality of parallel-extending knife blades 52 and 53 have their outer ends securely fastened to an insulating handle or rod 54, while the inner ends are pivoted to the switch jaws 44 and 47. Similarly, switch 40 blades 55 and 56 are provided with an insulating handle 57 and are respectively pivoted to switch jaws 47 and 50. The two movable switch elements thus have a single 45 point in common, viz., the central switch jaw 47.

An offset blade 58 is secured to the inner end of the blade 52, as best shown in Fig. 4, being slightly inclined toward the switch 50 jaw 45, while a similar offset blade 59 is secured to the inner end of the blade 56, inclining toward the switch jaw 49. If desired, the offset blades 58 and 59 may be made integral with the associated blades 52 55 and 56, though the preferred construction includes separate pieces that are riveted, as indicated at 60, to the corresponding knife blades of the double-pole portion.

Suitable wire-receiving terminals 61 are 60 bolted to the threaded portions of the switch jaws that extend beyond the rear side of the panel 42, in accordance with familiar switch-board practice. For the purpose of preventing movement of the double-pole 65 portions of the cut-out switch beyond the

desired normal position, cotter pins 62 and 63 extend transversely through the switch jaws 43, 46 and 49 and 45, 48 and 51.

As previously noted, the middle row of jaws 44, 47 and 50 are preferably provided 70 with suitable bolts and nuts, as is customary for providing a pivotal switch joint, while the insulating handles or rods 54 and 57 may be conveniently secured to the outer ends of the corresponding knife blades by 75 means of small screws 64.

It will be observed that the operating handles are offset from, or out of alignment with, the body portion of the corresponding switch blades. This construction is valuable 80 for interlocking purposes, as set forth below.

The operation of the cut-out switch apparatus that is illustrated in Fig. 2 and Fig. 3 may be briefly set forth as follows. Normally, the two movable switch elements occupy the illustrated positions corresponding to the diagrammatic showing in Fig. 1. To cut out the motor M1, the handle 54 is actuated to effect disengagement of the switch-blades 52 and 53 from the jaws 43 and 46, respectively, and to effect engagement of offset blade 58 with the jaw 45. Similar movement of the other switch element embodying the insulating handle 57 may be 95 effected for cutting out the other motor M2.

However, it should be noted that both of the movable switch elements cannot occupy the cut-out positions at the same time, since, for example, after the left-hand switch element embodying handle 54 has been thrown to its lower or cut-out position, attempted upward movement of the other switch element to its cut-out position is prevented by reason of the substantial alignment of switch blades 100 53 and 55 and the associated portions, whereby the blade 55 will strike a screw 64, and such interference will prevent the attempted movement of the other cut-out switch element.

Moreover, such interference will occur very quickly after the initial movement of the other switch element, by reason of the previously-described offset positions of the operating handles. In this way, it is made 115 impossible to establish the undesirable ground connection that it is possible to make with the prior art cut-out switch apparatus for two-motor equipments, which, as previously stated, comprises two independent double-pole, double-throw switches.

Referring to Fig. 5 and Fig. 6, the modification shown comprises two similar double-pole knife-blade switches that are illustrated in plan in Fig. 5. Normally, these 125 switches occupy diagonally opposite positions, thus corresponding to the preferred form of my invention, as previously described. Nine stationary contact members 73 to 81, inclusive, are arranged as already 130

set forth. A pair of parallel extending blades 82 and 83 have their inner ends pivotally mounted on jaws 74 and 77, respectively, while the outer ends engage jaws 78 and 76, respectively. A suitable operating handle 84 for the blades 82 and 83 is provided. The inner blade 83 is of the familiar rectangular shape, while the outer blade 82 is of the form shown in Fig. 6, 10 wherein a triangular portion or vertical extension 88 forms an integral part of the knife blade.

The other double-pole switch comprises parallel-extending blades 85 and 86, the inner ends of which are hinged to jaws 77 and 80, respectively, while the outer ends engage jaws 78 and 81, respectively. An operating handle 87 joins the blades 85 and 86, which correspond to blades 83 and 20 82, respectively. In other words, the outer blade 86 has the form shown in Fig. 6.

Consequently, either of the double-pole switches may be thrown to the opposite position to effect engagement of the triangular portion 88 of the blade 82 or the blade 86 25 with the jaw 75 or the jaw 79, respectively. However, the other blade of the actuated switch will not engage any jaw, since the limiting position of the blade portion 88 30 is such as to prevent such engagement. Thus, the modified form of cut-out switch shown in Fig. 6 may perform the same functions as the preferred form of switch that is illustrated in Fig. 2.

35 I do not wish to be restricted to the specific circuit connections, structural details or arrangement of parts herein set forth, as various modifications thereof may be made without departing from the spirit and 40 scope of my invention. I desire, therefore, that only such limitations shall be imposed upon my invention as are indicated in the appended claims.

I claim as my invention:

45 1. The combination with a pair of dynamo-electric machines, and means for effecting series-parallel control thereof, of switch means for cutting out either machine comprising two movable switch ele-

ments each adapted to function as either 50 a single-pole, single-throw switch or a double-pole, single-throw switch.

2. The combination with a pair of dynamo-electric machines, and means for effecting series-parallel control thereof, of 55 switch means for cutting out either machine comprising two movable switch elements having only one member in common.

3. The combination with a pair of dynamo-electric machines, and means for effecting series-parallel control thereof, of 60 switch means for cutting out either machine comprising two double-pole switch elements normally occupying opposite positions and having a single intermediate member in 65 common.

4. The combination with a pair of dynamo-electric machines, and means for effecting series-parallel control thereof comprising a series-connecting and a parallel- 70 connecting switch, of switch means for cutting out either machine comprising a movable switch element for directly interrupting connections to one machine and another movable switch element for directly interrupting the respective connections to said 75 switches.

5. The combination with a pair of dynamo-electric machines, of double-throw 80 switch means for cutting out either machine and having two members in substantial alinement for preventing the actuation of both switch means to the cutting-out position.

6. The combination with a pair of dynamo-electric machines, of switch means for cutting out either machine comprising two movable switch elements having a single intermediate stationary member in 85 common, whereby either element is prevented from being thrown to its cut-out position when the other element has already 90 been actuated to its cut-out position.

In testimony whereof, I have hereunto 95 subscribed my name this 30th day of Sept., 1919.

ANDREW H. CANDEE.
